UNITED STATES PATENT OFFICE.

ALFONSO MARIA MASSARI, OF ROME, ITALY.

ELECTRIC TELEPHONE-TRANSMITTER.

SPECIFICATION forming part of Letters Patent No. 689,503, dated December 24, 1901.

Application filed February 18, 1899. Serial No. 706,071. (No model.)

To all whom it may concern:

Be it known that I, ALFONSO M. MASSARI, commandant in the Italian Naval Reserve, residing at 163 Via Torino, Rome, Italy, have

5 invented certain new and useful Improvements in Electrical Telephone-Transmitters, of which the following is a specification, reference being had therein to the accompanying drawings.

10 My invention relates to electric telephone-transmitters, and has for its object an efficient transmitting instrument of simple construction that can be readily repaired when necessary and in which the transmission can be very delicately regulated.

Figure 1 is a side elevation, partly in section; and Fig. 2 is an end elevation of an instrument made according to my invention.

15 A is a plate of insulating material, preferably of ebonite, having a central opening therein and having the sleeves a a' formed on or attached thereto. B is the mouthpiece of the instrument and is removably attached to the insulating-sleeve a , preferably by means

20 of screws b . C is a hollow metal cylinder, which has an annular groove c on its outer periphery and has an internal recess formed at one end thereof, which fits over the insulating-sleeve a' and is secured thereto. D is

25 a tube having its free end screw-threaded. d is a disk or flat ring having a central opening therein to which one end of the tube D is attached, and d' is a short hollow cylinder attached to the edge of the flat ring or disk d .

30 The tube D, ring or disk d , and cylinder d' are of brass or other suitable conducting material and may be integral. The tube D passes through the plate A and cylinder C and has its screw-threaded end projecting beyond the

35 latter. S is a coiled spring situated between the ring or disk d and a shoulder formed by the aforesaid internal recess in the cylinder C. All these parts are mounted on the base-board P.

40 d^2 is a nut screwed onto the free end of tube D, and d^3 is a lock-nut for securing the said nut in position.

The cylinder d' contains a carbon block or cup E, situated opposite the central opening 45 in the ring or disk d and held in position and insulated by chalk F.

f is a piece of cotton or felt placed in the carbon cup E.

f' is a ring of cotton, and e is granulated carbon.

55 H is the diaphragm, and I is an elastic ring or tube of rubber or of other soft and insulating material which separates and insulates the diaphragm from the mouthpiece.

a^2 is an insulating-sleeve, preferably of ebonite, which fits into the tube D and has an annular flange a^4 at its outer end.

g g' represent a metal rod which passes through the sleeve a^2 and bears against the carbon block E, and g' is a nut for regulating the length of the rod g .

60 R is a sliding piece of metal having a longitudinal slot r therein. r' is a screw secured to the base P and on which the piece E slides. This sliding piece R has a knob or handle r^2 70 at one end thereof and has its opposite end forked, so as to slide into the groove c on the cylinder C, and thus secure the instrument to the base P. The ends of the fork are recessed and fit onto the screws r^3 when in depressed position. One end T of the line-wire is attached to the sliding piece R, and the other wire T' is attached to a contact-piece t , which bears on the metal rod g . The electric current is thus connected through the sliding piece R, cylinder C, tube D, ring or disk d , and the cylinder d' and through the rod g , carbon block E, and granulated carbon e , so that diaphragm H completes the circuit and by the variation of pressure, as usual, makes 85 the necessary variations for transmission of sounds.

80 When not in use, the diaphragm is supported between the cotton or felt pieces f f' and the rubber ring I. In Fig. 1 the parts are 90 shown as slightly separated for clearness of illustration; but it will be understood that in actual use they are brought into contact. When the instrument is in use, the diaphragm vibrates, and in so doing varies the pressure 95 of contact with the cylinder d' . The spring S normally tends to press the cylinder d' , ring or disk d , and tube D toward the diaphragm. The nut d^2 acts against the pressure of this spring and bears against the free end of the 100 cylinder C. The transmission is regulated by adjusting the pressure on the diaphragm,

and this is effected by screwing up or unscrewing the nut d^2 and its washer d^3 , and thus respectively decreasing or increasing the pressure on the diaphragm, by which 5 means a very delicate adjustment can be effected. The spring S tends to press ring or disk d and flange d' toward the diaphragm against the packing I ; but by means of the die or nut d^2 engaging the tube D said disk may be 10 held so as to bear with a greater or less pressure against the diaphragm.

In telephone-transmitters in which granulated carbon is used, as described, it sometimes happens that from a sudden shock or 15 other cause the granulated carbon becomes displaced and a part of it finds its way between the cotton wool and diaphragm to the cylinder d' , thus making contact and rendering the transmitters useless. Should this 20 happen in the case of an instrument made according to my invention, the latter may be quickly and easily repaired by means of removing the screws b , when the mouthpiece B and diaphragm H can also be removed, the 25 granulated carbon replaced, and these parts readjusted. By means of attaching the mouthpiece to the insulating-ring a and also insulating from the diaphragm by means of the rubber or like ring or tube I it is possible to 30 use a metal mouthpiece. By means of drawing back the sliding piece R into the position shown in dotted line in Fig. 2 contact between the terminal wire T and the cylinder C is broken, and the instrument can then also 35 be withdrawn from the base P .

Having now particularly described and ascertained the nature of my said invention and in what manner the same is to be performed, I declare that what I claim is—

40 1. In a telephone-transmitter of the character described, the mouthpiece forming a front support, an insulating-ring, and a diaphragm in position to bear against said ring when pressed against the same, a hollow metallic 45 cylinder bearing against the rear face near the outer edge of said diaphragm, and a spring tending to press said cylinder against the diaphragm, all combined substantially as described.

50 2. In a telephone-transmitter as described, the mouthpiece, a non-conducting ring behind said mouthpiece, the diaphragm having its front face resting against said ring when clamped, an annular metallic piece or hollow 55 cylinder bearing against the rear face of the diaphragm, a spring by which said hollow cylinder is pressed toward the diaphragm, and means for limiting the forward position of the hollow cylinder, all combined substantially as described.

3. In a telephone-transmitter, the mouthpiece and an insulating-ring behind the same, the diaphragm and a metallic ring bearing against the same near the outer edge thereof, a flat metallic ring connected to the said metallic ring, and a metallic tube connected to the inner edge of said flat ring, a spring bearing on the flat ring to press the same and its connected ring toward the diaphragm, and a collar supporting the tube and a nut engaging 65 said tube and collar, and serving to adjust the position of the ring which bears on the diaphragm, all combined substantially as described.

4. In a telephone-transmitter, the mouthpiece, diaphragm, and a metallic ring or hollow cylinder adjustable against the rear face of the diaphragm near the outer edge thereof, a carbon cup having its edge in contact with the rear face of the diaphragm, and an insulated metallic rod held by spring-pressure against the bottom of said carbon cup, the outer metallic ring being in electrical connection with one terminal, and the insulated rod with the other terminal, all combined substantially as described. 75

5. In a telephone-transmitter, the mouthpiece removable from the front, the diaphragm clamped against the rear face of the mouthpiece by an adjustable ring, a carbon cup having its edge against the rear face of the diaphragm within the adjustable ring, and a spring-pressed rod bearing against the center of said carbon cup, all combined substantially as described. 90

6. In a telephone-transmitter, the diaphragm supported at the edge and removable from the front, a carbon cup having its edge against the rear face of the diaphragm, a packing of felt or like material within and without the carbon cup and bearing on the diaphragm, and an insulating-support of chalk surrounding the base of the carbon cup, all combined. 100

7. In a telephone-transmitter, the base or support having a hole therein, a hollow metallic cylinder in said hole in the base, and supporting the operating mechanism of the phone, a groove in said cylinder in rear of the base, and a sliding fork engaging said groove, whereby the fork may clamp the phone to its base, or permit its removal from the front thereof, substantially as described. 105

In testimony whereof I affix my signature in presence of two witnesses.

ALFONSO M. MASSARI.
